The ornamental design for a joint for structural materials, as shown and described.

DESCRIPTION

FIG. 1 is a front, top, right-side perspective view of the joint for structural materials;

FIG. 2 is a rear, bottom, left-side perspective view thereof; and,

FIG. 3 is a front elevational view thereof, the rear elevational, right-side elevational, left-side elevational, top plan, and bottom plan views (not provided) being identical.

The broken lines depict unclaimed portions of the joint, and thus form no part of the claimed design.
